CLAIM

I claim the ornamental design for a spacer chamber for an inhaler, as shown and described.

DESCRIPTION

FIG. 1 is a left perspective view of a spacer chamber for an inhaler showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The subject matter shown in dashed lines, and any surface of the design not shown, including interior surfaces, form no part of the claimed design.
